DRAFT RIGGING

James E. Echols and Posey G. Stultz, Roanoke,
Va., assignors to The Symington Company,
New York, N. Y., a corporation of Maryland

Application September 17, 1927
Serial No. 220,255

8 Claims. (Cl. 213—50)

This invention relates to draft rigging and, more particularly, to the construction of the yoke, associated combined backstop and center filler casting, and rear follower.

5 The principal object of our invention, generally considered, is to provide a draft rigging involving a yoke with a curved rear end fitting the correspondingly curved front wall of an associated combined backstop and center filler casting, the lower wall of said casting being formed to interlock with an associated center plate, whereby longitudinal shifting thereof is obviated.

An object of our invention is to provide a center filler member with side walls adapted for 15 connection to associated center sills and a bottom wall to which an associated center plate is connected, said bottom wall having depending lugs adapted to lie forwardly and rearwardly of said center plate and prevent longitudinal shifting 20 thereof.

Another object of our invention is to provide a backstop casting adapted to cooperate with an associated yoke, the rear end of which is preferably bent into semi-cylindrical form, the 25 front wall of said backstop being correspondingly curved, a rear follower member being provided with a correspondingly curved rear wall fitting the curved portion of the yoke and a front wall adapted to engage associated cushioning 30 mechanism.

A further object of our invention is to provide a backstop casting with a front buffering wall supported by means of a substantially horizontal cross web extending between the side walls thereof, said cross web being reinforced at its rear edge by an upwardly extending flange and, intermediate the front and rear edges, by a depending flange.

An additional object of our invention is the 40 provision of draft rigging embodying a horizontal yoke with a curved rear end associated with a rear follower or yoke filler through which buffering forces may be directly transmitted to an associated backstop thereby relieving the rear end 45 of said yoke from strains.

Other objects and advantages of the invention relating to the particular arrangement and construction of the various parts will become apparent as the description proceeds.

50 Referring to the drawings illustrating our invention, the scope whereof is defined by the appended claims:

Figure 1 is a plan of part of the underframe of a car shown partly in horizontal section and illustrating one embodiment of our invention.

Figure 2 is a central vertical longitudinal sectional view of Figure 1.

Figure 3 is a transverse sectional view on the line 3—3 of Figure 1 looking in the direction of the arrows.

Figure 4 is a fragmentary transverse sectional view on the line 4—4 of Figure 2 looking in the direction of the arrows.

Figure 5 is a fragmentary sectional view on the line 5—5 of Figure 2 looking in the direction of the arrows.

Figure 6 is a fragmentary plan corresponding to part of Figure 1 but showing another embodiment of our invention.

Figure 7 is a central vertical longitudinal sectional view of the embodiment illustrated in Figure 6.

Figure 8 is a transverse sectional view on the line 8—8 of Figure 7 looking in the direction of the arrows.

Referring to the drawings in detail, like parts being designated by like reference characters, and first considering the embodiment of our invention illustrated in Figures 1 to 5, inclusive, there is shown a portion of the underframe of a car with center sills 1 connected by a cover plate 2 at their upper portions and joining with the end sill 3, the end plate 4 and the striking casting and sill tie member 5. The flooring 6 of the car may overlie the cover plate 2 and extend between the same and the end sill 3 as illustrated.

Between the center sills 1, extends the draft rigging comprising a coupler 7, a yoke 8, a front follower 9 and a rear follower 10. The coupler and yoke are shown connected together by a front draft key 11 and connected to the sills 1 for the transmission of draft forces by a rear draft key 12 which also supports the front follower 9. Both of said draft keys extend through correspondingly slotted portions in the sills 1, 95 said sills being preferably reinforced by correspondingly slotted cheek plates 13 through the corresponding slots in which the draft keys 11 and 12 pass. The coupler illustrated is of the swivel butt type with a swivel block portion 14 pivoted to the butt of the main coupler 7 by means of a pivot pin 13, as will be understood.

The front follower 9 is, as usual, provided with a coupler centering lug 16, in this case, engaging in a corresponding pocket in the swivel block 14. The rear portion of the yoke 8 preferably rests on and is supported by angular members 17 formed with vertical flanges connected to the associated sills and with horizontal flanges underlying and supporting the respective arms 110

- of the yoke 8. Cushioning mechanism, indicated diagrammatically by dot and dash lines, is received between the arms of the yoke and front and rear followers 9 and 10, respectively.
- 5 In order to hold the rear follower in proper position, the same is preferably provided with outstanding flanges 10' overlying and underlying the curved portion of the yoke 8 whereby vertical displacement of said follower is obviated.
- 10 The draft keys 11 and 12 may be retained in any usual or desired manner but, in the present embodiment, I have shown them held in place by means of novel key retainers 18. Each key retainer preferably comprises an upper flanged portion 19 preferably connected to the upper flange of the associated center sill by the common rivet 20 which serves for connecting said center sill to the cover plate and flooring of the car. In order to obviate the necessity of removing the rivet 20 and thereby disturb the lading when the car is loaded, when it is desired to remove the draft key, said key retainer 18 is preferably provided with a removable extension 21 which overlies the head of the key with which it is employed and which may be removed for the removal of said key by merely cutting the rivet or other connecting means 22 between the upper and lower portions 19 and 21, respectively.
- 15 The rear end of the yoke 8 is preferably bent into semi-circular or semi-cylindrical form and is adapted to engage the front face of an associated combined backstop and center filler casting 23. Said casting is provided with side walls 24 connected with the associated center sills 1 as by means of rivets 25 and formed with a front wall 26 curved to correspond with the curvature of the rear end of the yoke 8, whereby said yoke snugly fits thereagainst. For adequately reinforcing said front wall 26, an intermediate horizontal web 27 is provided extending rearwardly therefrom and joining the side walls 24 of the casting. The rear edge of said web 27 is reinforced by an upstanding flange 28 and a depending flange 29 is provided forwardly of the flange 28 intermediate the same and the front wall 26. Said front wall is preferably additionally reinforced by a plurality of longitudinally extending reinforcing vertical webs 30 which extend rearwardly to the flanges 28 and 29. The side walls 24 are preferably joined to the outer edges of the curved front wall 26 by means of diagonally disposed webs 31.
- 20 The rear portion of the combined casting 23 is provided with a bottom wall 32 to which the center plate 33 is adapted for connection as by means of rivets or the like 34. As additional means for preventing longitudinal shifting of the center plate, depending lugs 35 are provided extending forwardly and rearwardly of the center plate and between which the upper wall thereof is snugly embraced. The bottom wall 32 of the casting is preferably braced with respect to the side walls by means of transverse reinforcing webs 36 and by means of a central transversely disposed web 37, or one adapted to normally lie on the vertical central plane of an associated bolster, the upper edge of which is preferably flanged, as indicated at 38, to more adequately strengthen the same. The combined casting is strengthened longitudinally, in addition to the webs 30 heretofore described, by a central longitudinal web 39 extending from the flanges 28 and 29, flaring rearwardly to meet the front lug 35 and the upper flanges 38, from whence it is continued at uniform height below said flanges to the rear edge thereof, from where it tapers rearwardly to merge with the bottom wall of the casting. The lower edges of the sills 1, along the sides of the combined casting 23, are reinforced by angle irons 40, the vertical flanges 41 of which are connected to the sills 1 and lie between said sills and the side walls 24 of the casting and the lower horizontally extending flanges 42 of which underlie said casting, the bottom wall of which is preferably upwardly offset to receive the same.
- 25 Referring now to the embodiment of our invention illustrated in Figures 6, 7 and 8, a construction is there disclosed which is similar to that of the first embodiment except that the rear follower or yoke filler 10' engages the backstop and center filler casting 23a directly upon rearward movement of the rigging instead of engaging merely the rear end of the yoke which, in turn, engages the combined casting. As in the previous embodiment, there are center sills 1a between which is connected a combined backstop and center filler casting 23a to which is attached the center plate 33a, the forward end of said casting involving a front wall 26a, the front face of which is curved or pocketed to receive the corresponding curved rear end of the yoke 8a. Said yoke is, as in the previous embodiment, supported adjacent its rear end by angular members 17a, that portion of the yoke and associated members forwardly of the supporting members 17a being as shown in Figures 1 to 5, inclusive, or of any desired construction.
- 30 The rear follower or yoke filler 10a is curved on its rear face to fit the curved end of the yoke but is provided with upstanding and depending portions 43 which are preferably provided with flat rear faces 44 adapted to engage corresponding stop portions 45 disposed forwardly of the curved wall 26a of the combined casting whereby engagement between the faces 44 and the stops 45 is effected prior to the engagement of the yoke 8a against the curved web 26a of the combined casting. The stop portions 45 are preferably reinforced by horizontal rearwardly extending webs 46 which preferably continue past the upper and lower edges of the curved web 26a and merge at their ends into the side walls 24 of the casting. The reinforcing webs 30a are formed with inclined free edges which extend from the extreme upper and lower edges of the stops 44 to the upper and lower edges of the reinforcing flanges or webs 28a and 29a, respectively. Except as specifically described in connection with the present embodiment, the same may correspond with that of the first embodiment.
- 35 From the foregoing disclosure, it will be seen that we have devised a construction for railway draft rigging in which the center plate is securely retained in place with respect to a combined backstop and center filler casting by lugs extending forwardly and rearwardly of said center plate, said lugs being preferably of less width than the width of the casting so as to extend between the inner margins of the inwardly extending flanges of reinforcing angles on the lower edges of the center sills, as shown most clearly in Figures 1 and 6. The buffing load transmitted through the draft gear is received from the rear yoke filler through the back end of the arcuate yoke where it is directly transmitted to the correspondingly curved or pocketed front face of the combined casting as all three elements will fit together with the avoidance of substantially all forces on buff
- 80 85 90 95 100 105 110 115 120 125 130 135 140 145 150

but direct compression. The yoke filler is held in place, in accordance with the first embodiment, by top and bottom flanges and, in the second embodiment, by the upwardly and downwardly extending portions which extend transversely above and below said yoke. The buffing face of the combined casting is supported by means of a cross web which is, in turn, reinforced by upwardly and downwardly directed flanges. Provision is made for centering the rivets connecting the combined casting with the sills by omitting the bottom wall 32 of the casting for a portion of the length thereof.

In the alternative construction, provision is made for relieving the rear end of the yoke from buffing strains and transmitting such directly through the rear follower or yoke filler to the backstop. Said backstop is preferably provided with a pocket or curved cut away portion in the front face to prevent engagement of the yoke with the backstop prior to engagement of the rear follower therewith. The yoke filler is provided with a flat front striking face with upper and lower flat rear striking faces and a curved contour intermediate the upper and lower faces to cooperate with the rear end of the yoke. The backstop casting is preferably formed with upper and lower bridges extending between the sills and arranged to take the force from the upper and lower flat faces of the rear yoke filler.

Having now described our invention, we claim:

1. In combination with the center sills of a car, a center filler member connected therebetween, reinforcing angular members connected to said center sills on either side of said filler member and provided with lower inwardly extending legs underlying said center filler member, lugs depending from the bottom of said filler member between said legs, and a center plate connected to the bottom thereof and lying between said lugs whereby the same is prevented from shifting.

2. A combined backstop and center filler casting comprising side walls adapted for connection to associated center sills and a front wall adapted to receive buffing forces from an associated yoke, said casting being formed with a bottom wall adapted for connection with an associated center plate and provided with front and rear anchoring lugs adapted to extend forwardly and rearwardly of said center plate, said bottom wall being omitted from the front anchoring lug to the yoke engaging wall to provide apertures for centering the rivets by means of which said casting is connected to the center sills.

3. In combination with railway vehicle sills, a center filler member disposed therebetween and connected thereto, means connected to said sills on either side of said filler member and formed with flanges extending toward each other and underlying said filler member for the support of the same, lugs depending from the bottom of said filler member between said supporting flanges, and a center plate connected to the bottom of said filler member and lying between said lugs.

4. A combined backstop and center filler casting comprising spaced side walls adapted for connection to associated sills, and a front wall formed with a pocket adapted to receive the rear end portion of an associated yoke, said casting having a bottom wall provided with front and rear lugs adapted to respectively lie forwardly and rearwardly of an associated center plate, said bottom wall forwardly of said front lug being

omitted to facilitate connection of the side walls to the sills.

5. A combined backstop and center filler casting comprising spaced side walls adapted for connection to associated sills, and an end wall 80 cylindrically curved about a normally vertical axis to form a pocket adapted to nestingly receive the correspondingly formed rear end portion of an associated yoke, said casting having a lower wall provided with front and rear lugs 85 adapted to respectively lie forwardly and rearwardly of an associated center plate, a portion of said lower wall being omitted to facilitate connection of the side walls to said sills.

6. An integral casting comprising a backstop 90 portion and a center filler portion, said casting having side walls adapted for connection with associated center sills and the backstop portion comprising a front wall with a horizontally concavely curved front face adapted to receive buffing forces from a correspondingly curved end of an associated yoke, said wall being reinforced by means of a generally horizontal web extending between the side walls and merging into said front wall, the center filler portion comprising 100 a transversely extending generally vertical web adapted to normally lie on the vertical central plane of an associated bolster, said horizontally disposed web terminating at its rear edge in a bracing flange extending transversely of said 105 casting and disposed forwardly of said transverse web, a plurality of generally vertical longitudinal webs on said horizontal web extending rearwardly from said front wall and terminating at said bracing flange, and a web extending between 110 said bracing flange and transverse web.

7. In combination with the center sills of a car, a combined backstop and center filler member connected therebetween, a yoke mounted between said center sills and provided with a curved 115 end adapted to be received adjacent the front face of the combined filler member, said front

face, for that purpose, being pocketed for receiving the end of said yoke, the vertical surface defining said pocket being curved to correspond 120 with the curvature of the yoke end, a rear yoke filler mounted adjacent the rear end of said yoke and formed with a correspondingly curved rear face engaging the curved portion of the yoke, a front face adapted to engage associated mechanism and provided with upward and downward extensions beyond said yoke, said upward extension having laterally extending portions overlying the arms of the yoke, said extensions and portions being provided with flat striking faces, 125 130 and stop portions provided on the combined member above and below the pocket portion for engagement by the flat striking portions on the rear of the yoke filler, said curved face on said combined filler member being slightly spaced 135 from said yoke rear end in normal assembly.

8. In combination with the center sills of a car, a combined backstop and center filler casting connected therebetween, a yoke mounted between said sills, provided with arms, and having a 140 curved end adapted to be received adjacent the front face of the combined filler member, said front face, for that purpose, being pocketed for receiving the end of said yoke, the vertical surface defining said pocket being curved to correspond with the curvature of the yoke end, a rear follower mounted adjacent the rear end of said yoke and formed with a correspondingly curved rear face engaging the curved portion between 145 the arms of said yoke, a front face adapted to 150

engage associated mechanism and provided with upward and downward extensions beyond said yoke, said extensions having top and bottom lateral portions respectively overlying and under-
5 lying the arms of the yoke, said upward and downward extensions and said lateral portions being provided with flat striking faces, and stop portions provided on the combined casting above

and below the pocket portion for engagement by the flat striking faces on the rear of the rear follower, said curved face on said combined filler casting being slightly spaced from said yoke rear end in normal assembly.
